[57] **CLAIM**

The ornamental design for container for small electronic structural components, as shown and described.

DESCRIPTION

FIG. 1 is a perspective view of a container for small electronic structural components showing our new design;

FIG. 2 is an exploded perspective view thereof;

FIG. 3 is an end elevational view of the bottom portion thereof taken along line 3—3 of FIG. 2;

FIG. 4 is a side elevational view of the bottom portion taken along line 4—4 of FIG. 2;

FIG. 5 is an end elevational view of the bottom portion taken along line 5—5 of FIG. 2;

FIG. 6 is a side elevational view of the bottom portion taken along line 6—6 of FIG. 2;

FIG. 7 is an end elevational view of the top portion taken along line 7—7 of FIG. 2;

FIG. 8 is a side elevational view of the top portion taken along line 8—8 of FIG. 2;

FIG. 9 is an end elevational view of the top portion taken along line 9—9 of FIG. 2; and

FIG. 10 is a side elevational view of the top portion taken along line 10—10 of FIG. 2.

Fig. 7

Fig. 8

Fig. 9
